DESIGN FOR A PENCIL

Raymond A. Weissenborn, Montclair, N. J.

Application October 8, 1936, Serial No. 65,200

Term of patent 3½ years

To all whom it may concern:

Be it known that I, Raymond A. Weissenborn, a citizen of the United States of America, residing at Montclair, county of Essex, and State of New Jersey, have invented a new, original, and ornamental Design for a Pencil, of which the following is a specification, reference being had to the accompanying drawing, forming part thereof.

The characteristic feature of the design resides in the mushroom shaped head and its directly subject cylindrical shank surmounting an elongated cylindrical rod of the same diameter as said shank.

I claim:

The ornamental design for a pencil, as shown and described.

RAYMOND A. WEISSENBORN.
